F. C. BROCK.
COVERING FOR THE BACKS AND SEATS OF AUTOMOBILES.
APPLICATION FILED APR. 11, 1918.

1,303,020.

Patented May 6, 1919.

WITNESS:

F. DeWitt C. Brock, INVENTOR.

BY
Edwin P. Parker
ATTORNEY.

UNITED STATES PATENT OFFICE.

FREDERICK C. BROCK, OF COLUMBUS, OHIO.

COVERING FOR THE BACKS AND SEATS OF AUTOMOBILES.

1,303,020.

Specification of Letters Patent. Patented May 6, 1919.

Application filed April 11, 1918. Serial No. 227,847.

To all whom it may concern:

Be it known that I, FREDERICK C. BROCK, a citizen of the United States of America, residing at Columbus, in the county of 5 Franklin and State of Ohio, have invented certain new and useful Improvements in Coverings for the Backs and Seats of Automobiles, of which the following is a specification.

10. My invention relates to coverings for the backs and seats of automobiles and aims to provide such a covering for this purpose that little expert tailoring will be necessary to the production of these coverings 15 and that each covering when produced will be capable of fitting several models of automobiles. It is rather customary in the automobile industry for each manufacturer to somewhat vary the model of car that he 20 puts out each year and in the past it has been customary among the manufacturers of seat covers to provide a pattern for each different model and then to furnish identical coverings for the seats and backs of each 25 "model" of car.

The present invention resides in the provision of a covering of the type described. This covering, unlike those of the prior art, is made in one piece. Furthermore, it is in 30 such form that it both fits the backs and seats of the comparatively wide range of automobiles and is readily removed therefrom to be washed as a flat piece. It is worthy of note that all other coverings of 35 this character require a covering for each seat cushion and a separate cover for the back and sides of each seat.

The preferred embodiment of my invention is shown in the accompanying drawings 40 wherein similar characters of reference designate corresponding parts and wherein:

Figure 1 is a development of the one piece covering utilized by me.

Fig. 2 is a front perspective view of an 45 automobile seat with the seat-cushion removed and the seat flap thrown back.

Fig. 3 is a front perspective view of the structure shown in Fig. 2 with the addition of the seat cushion, although the flap shown 50 for covering the seat is still thrown back.

Fig. 4 is a perspective view showing the covering in normal operative position.

In the drawings, the covering is shown 55 as a unitary structure comprising a main back piece 1 with arm pieces 2 and 3 all of flat material and having their under edges

curved to conform to the general contour of the upper edge of the seat structure. The arm pieces 2 and 3, though forming rear extensions of the back piece 1, are partially 60 separated therefrom at 4 and 5 where they are designed to overlap and permit spreading of the covering without resulting in such a gap that the seat or back thereof will be exposed to view or to contact with the 65 clothes of the occupant. The arm pieces 2 and 3 are shown in dotted lines in Fig. 1 and the back edges thereof, in this figure, are increased in length. This increase in length exists for a considerable depth from 70 each edge and serves as extensions 20 which are designed when the covering is in operative position to underlap the back piece 1 as at 4 in Fig. 4. It is important to note that the arm coverings do not hook over the 75 edges of the arm pieces and, for this reason, each cover is applicable to a number of different models of cars.

Formed on the bottom of the back piece 1 is an extension 6 having side flaps 7 and 8 80 designed to be tucked in between the sides of the seat cushion and the arm-pieces. In addition, this extension 6 has a flap 9 which normally extends down in front of the seat structure. At this point it should be noted 85 that preferably neither the extension 6, the flaps 7 and 8, nor the flap 9 are ever secured. They are merely tucked in between the cushions when desirable.

The application of this device is facilitated by the use of a cord 10 which is so laced, preferably through eyelets 11, that it forms loops at regular intervals around the outer edges of the back piece 1 and the arm-pieces 2. By means of these loops, the outer 95 edges of these portions are readily attached to hooks or buttons disposed at regular intervals around the upper edges of the back and arm-pieces.

In conjunction with the loops just described and located at the juncture of the piece 1 and the piece 6 is a loop-formation 12 extending through eyelets 13 and which cooperates with loop portions 14 in eyelets 15 of the arm-pieces to hold the back and 105 arm pieces firmly in position. These loops 12 and 14 are designed to be attached to hooks or similar functional elements on the seat structure behind and around the sides of the seat cushion.

In operation the device is normally disposed as in Fig. 4, being capable of appli-

cation to seat structures of varying sizes because it is in the nature of a flat piece of material.

One of the advantages of the loose piece 6 is illustrated by Fig. 3, where it is seen that this piece 6 is thrown back to cover the back of the seat and to simultaneously protect its own upper surface. For instance, if it is allowed to stand in a dusty community, the 10 flap 6 may be thrown back so that when the occupant arrives he need only turn down the flap shown in position in Fig. 4 and the clean back and flap will protect him from the accumulated dirt on the seat and on the 15 upper side of such flap. A similar situation would arise where it might be necessary to turn the car over to workmen with comparatively greasy clothing.

On the other hand, the device being attachable much more easily than a "seat cover" may be applied as a covering for the seats of an automobile on display, in which event the covering 6 will either protect fancy cushion cloth or may be thrown back 25 for inspection of the cushions. This last use is very important, because the cloth seats of a fine limousine deteriorate very rapidly when prospective purchasers persist in sitting on them, until finally the car cannot be 30 sold as a new car without expensive renovation of its seats.

Yet again, this covering may be used as a supplement to the normal seat cover, either in the garage or elsewhere, being placed

over the seat covers until special occasions, 35 when it may be removed readily or may be thrown back in the manner previously described.

Finally it is a very important and obvious fact that the device may be sold cheaply 40 because of its simple construction and may be washed readily.

I claim—

1. A covering for the backs and seats of automobiles comprising a piece for covering 45 the back and extensions formed integral therewith for extending around onto the arms, said back-piece and extensions being partially separated by a slit with overlapping edges to permit spreading. 50

2. A covering for the backs of automobile seats comprising a piece for covering the back and extensions formed integral therewith for extending around onto the arms, said back-piece and extensions being partially separated by a slit, and a flap on one 55 of the edges of said slit for underlapping the other edge of said slit.

3. A covering for the back and arms of an automobile seat comprising a single piece 60 which extends along the back and only part way along the arms, said back-piece and extensions being partially separated by a slit, and a flap on one of the edges of said slit 65 for underlapping the other edge of said slit.

In testimony whereof I hereby affix my signature.

FREDERICK C. BROCK.
